US0D1000323S

(12) **United States Design Patent** (10) **Patent No.:** **US D1,000,323 S**
(45) **Date of Patent:** **** Oct. 3, 2023**

(54) **HITCH COVER**

(71) Applicants: **Richard P. Rizzuto**, Basking Ridge, NJ (US); **Victor T. Rendano, Jr.**, Sarasota, FL (US)

(72) Inventors: **Richard P. Rizzuto**, Basking Ridge, NJ (US); **Victor T. Rendano, Jr.**, Sarasota, FL (US)

(**) Term: **15 Years**

(21) Appl. No.: **29/785,541**

(22) Filed: **May 26, 2021**

(51) **LOC (14) Cl.** **12-16**

(52) **U.S. Cl.**

USPC **D12/162**

(58) **Field of Classification Search**

USPC D12/159, 160, 161, 162, 203, 223, 317,

D12/400; D21/777, 810

CPC . B60D 1/30; B60D 1/58; B60D 1/241; B60D

1/363; B60D 1/06; B60D 1/52
